UNITED STATES PATENT OFFICE.

HENRY C. DOBSON, OF NEW YORK, N. Y.

BANJO.

SPECIFICATION forming part of Letters Patent No. 294,451, dated March 4, 1884.

Application filed January 18, 1883. (No model.)

To all whom it may concern:

Be it known that I, HENRY C. DOBSON, a resident of the city, county, and State of New York, have invented certain Improvements 5 in Banjos, Drums, and other Analogous Instruments, of which the following is a specification.

This invention applies to all musical instruments which are constructed with a parchment head stretched over a cylindrical rim or ring—such as banjos, drums, and tambourines—and it relates to the construction of the ring or rim over which the head is stretched. These rings have been heretofore made in various ways. In some instruments a flanged dome-shaped ring spun up from sheet metal has been placed on the top of the cylindrical ring, between it and the parchment, as shown in my Patent No. 249,321, dated November 8, 15 1881. That patent illustrates what I believe to be the most perfect and desirable construction heretofore made.

Figure 1 of the accompanying drawings is a plan of the bottom or under side of a banjo constructed according to my present invention, only a portion of the handle being shown. Fig. 2 is a transverse section thereof cut in the plane of the line 2 2 in Fig. 1, but drawn to a larger scale. Fig. 3 is an enlarged fragmentary section of the ring, showing its construction of three pieces. Fig. 4 is a similar view, showing a modified construction of two pieces. Figs. 5 and 6 are fragmentary sections of the ring, showing modified shapes; 30 and Fig. 7 is an elevation of a drum made according to my present invention, one side thereof being in section.

Referring to Figs. 1 and 2, let A designate the handle; B, the ring or rim; C, the parchment head stretched thereon; D, the straining-ring, and E E the clamps or tightening-screws for drawing down the ring D and straining the head. With the exception of the ring B, these parts are or may be all constructed as shown in my said patent. The ring B, I now make of metal, and of tubular form in cross-section, as best seen in Fig. 2. The metal tube (lettered a) is best formed of sheet-brass, and it is preferably re-enforced 45 50 by a hoop of wood, b, arranged within it, as

shown; but this hoop should not fill all the space within the tube, as it is desirable that the latter shall be at least partially hollow in order to enhance the tone of the instrument by its bell-like reverberation. The wooden hoop b serves to stiffen the tubular ring, and permits the use of thin sheet metal in the formation of the tube a, by which the resonance of the latter is increased. At intervals around the ring B holes or orifices c c are formed through the metal of the tube a, communicating with the hollow interior of the ring. These holes facilitate the escape of the sound-vibrations from the interior of the ring and augment the volume of sound given out by the instrument, as well as improving its tone. This hollow ring B, thus perforated, forms a sort of sounding-box, the effect of which in amplifying and improving the tone of musical instruments is well known. The upper side of the tube a is 60 swelled or dome-shaped in cross-section, being in shape similar to the corresponding portion of the sheet-metal ring in my said patent, and for the same purpose—namely, to afford a rounded corner, over which the parchment 65 may be bent, and to provide a crowned elastic and resonant support for the parchment for some distance inward from the periphery of the instrument.

The tubular ring B may be made in many 70 ways. It is possible to bend a straight metal tube, made in any of the known ways, into ring shape and join its ends by soldering or otherwise; but on account of the extreme difficulty of this method I prefer to make the 75 ring of two or more spun pieces of sheet metal, with seams extending around it, as shown in Figs. 3 and 4. In Fig. 3 three pieces are employed, lettered d, e, and f. The piece d is a mere strip of sheet metal bent into hoop shape 80 and its ends joined together. The pieces e and f are spun up from washer-shaped blanks or rings of sheet metal to the shape shown, both being alike, except where they lap. The three rings or pieces thus made are lapped 85 and soldered together, or they may be otherwise fastened together, either by lapping them or joining them edge to edge. In Fig. 4 but two pieces are used, lettered g and h. Both are spun up from cylindrical hoops similar to 90 95 100

d. The hoop or piece *h* forms the inside of the ring *B*, while *g* forms the outside thereof, and they are seamed together at top and bottom.

5 The annular tube *a*, forming the ring *B*, may be of any one of various shapes in cross-section. Two suitable shapes are shown in Figs. 5 and 6.

The standards *i* for the tightening-screws 10 *E E* may be fastened to the ring *B* in several ways. In Fig. 2 they are shown as provided with screw-shanks which screw into the wooden hoop *b*. In Fig. 5 they are shown as riveted to the outer portion or side of the tubular ring, in which case, if the tube is made of 15 thin metal, it should be lined with a ring of thicker metal, through which to rivet. In Fig. 6 the standard *i* has a screw-shank, which passes entirely through the tubular ring *B*, and has a nut, *j*, screwed on its end. To prevent the collapsing of the ring when tightening the nut, a washer, *k*, is placed in the hollow of the ring before inserting the shank, and the latter is passed through both thicknesses 20 of the ring and the intervening nut.

The handle *A* of the banjo is or may be attached to the ring *B* in the usual manner, and the banjo is strung in the ordinary way.

Fig. 7 shows a drum the ring or cylinder 30 of which is made according to my present invention, but which is otherwise of the ordinary construction.

I am aware that a banjo has been patented 35 the ring or rim of which is made wholly of metal, with its top and bottom edges flanged or spun over internally for a short distance; but I am not aware that any banjo has ever yet been made or patented the ring or rim of which consists of an annular metal tube. I 40 am also aware that banjos have been made with a wooden rim or ring mounted on legs above an annular wooden sounding-box; but this is not the equivalent of my invention, as in my banjo the rim and sounding-box are identical, the annular tube of resonant metal 45 serving the purposes of both. Another banjo has the usual wooden rim with a wire-like ring or slender metallic tube elevated on standards slightly above the rim, with the parchment stretched over said metallic ring.

I claim as my invention—

1. A banjo or other parchment-head instrument, the main rim of which, composing the body of the instrument, is made of an annular metallic tube forming a sounding-box, substantially as set forth. 55

2. In a banjo or other parchment-head instrument, the combination of a rim made of an annular metallic tube forming a sounding-box, a parchment head strained over said rim, 60 a series of standards fixed to said rim, a straining-ring for stretching said head, and tightening devices engaging said standards for drawing down said ring, substantially as set forth.

3. A banjo or other parchment-head instrument, the main rim of which, composing the body of the instrument, is tubular and made from sheet metal, stiffened by a hoop of wood extending around it and within the hollow of 65 said tube, substantially as set forth. 70

4. A banjo or other parchment-head instrument, the ring or rim of which consists of an annular tube of sheet metal provided with apertures or sound-holes *c c*, affording communication between the annular hollow or cavity 75 thereof and the external air, substantially as set forth.

5. A banjo or other parchment-head instrument, the ring or rim of which is formed of sheet metal in tubular form, the annular tube 80 being built up of two or more rings of sheet metal with annular seams, substantially in the manner set forth.

6. The ring or rim of a banjo or other parchment-head instrument, built up of three 85 rings of sheet metal, two of which have outer and inner flanges and intermediate swelled or convex portions to form the top and bottom of the rim, while the third is of cylindrical shape to form the outer periphery of the rim, 90 substantially as set forth.

In witness whereof I have hereunto signed my name in the presence of two subscribing witnesses.

HENRY C. DOBSON.
